LUGGAGE TRAY

William C. Chesnut, Racine, Wis., assignor to
 Hartman Trunk Company, Racine, Wis., a corporation of Wisconsin

Application October 20, 1938, Serial No. 235,989

4 Claims. (Cl. 190—41)

This invention relates to improvements in luggage trays.

The present invention is concerned particularly with that type of hand luggage wherein there is a garment tray having a support adjacent the rear wall thereof for removably receiving a plurality of hangers and wherein there is a flap swingable over said tray and hangers around which the free ends of garments supported on the hangers may be folded. Heretofore the garment folding flap has been hingedly connected to the rear of the tray by a flexible section of fabric and in Bracken Patent No. 1,842,578 this flexible section permits the flap to adapt its closing position to the number of garments being carried and to the number of hangers on the support. This flexible section is desirable as far as accomplishing the object sought is concerned but is, however, in certain conditions of use inclined to sag.

The present invention contemplates the provision of a novel and improved form of hinge connection for the tray flap wherein the flap is connected to the tray by spaced pivot members, such as trunnions, and wherein said pivot members are so supported as to permit movement thereof in a direction perpendicular to the bottom of the tray whereby the closing position of the tray is automatically adapted to the number of garments being carried.

A further object of the invention is to provide in a luggage tray as above described novel brackets for cooperation with the flap trunnions.

A more specific object of the invention is to provide in a structure as above described brackets having elongated openings which project above the upper edge of the rear wall of the tray whereby the garment folding flap may be swung rearwardly over said rear wall.

A further object of the invention is to provide a structure wherein said projecting portions of the brackets are formed with means engaged by the ends of the trunnions, when the latter are in elevated position, for preventing transverse movement of the trunnions and flap.

A further object of the invention is to provide a luggage tray wherein the garment folding flap is formed of a covered wire frame and wherein the wire forming said frame is bent outwardly on opposite sides and doubled upon extensions of a connecting wire frame part to provide flap trunnions formed integral with said wire frame.

Other objects of the invention are to provide a luggage tray which is simple and inexpensive in construction, strong and durable, neat in ap-

pearance, and well adapted for the purpose described.

With the above and other objects in view, the invention consists of the improved luggage tray and all its parts and combinations as set forth in the claims and all equivalents thereof.

In the accompanying drawing illustrating one complete embodiment of the preferred form of the invention in which the same reference numerals designate the same parts in all of the views:

Fig. 1 is a perspective view of the improved luggage tray;

Fig. 2 is a plan view thereof on a larger scale, 15 part of the garment folding flap being broken away;

Fig. 3 is an enlarged sectional view taken on line 3—3 of Fig. 2 showing the position of the parts when a single suit is being carried in the tray;

Fig. 4 is a similar view showing the position of the parts when two suits are being carried in the tray;

Fig. 5 is an enlarged perspective view of one 25 of the trunnion supporting brackets;

Fig. 6 is a fragmentary detailed view taken on line 6—6 of Fig. 2; and

Fig. 7 is a fragmentary detailed view of one of the rear corners of the garment folding flap showing how the trunnions are formed from the wire frame.

Referring more particularly to the drawing, the numeral 8 designates generally the garment tray, which tray is formed from any suitable material and which comprises a bottom 9, side walls 10 and 11, and a rear wall 12. Looped straps 13 forming handles may be secured to the side walls 10 and 11 to facilitate lifting the tray out of a suitcase.

40 Disposed adjacent the inner side of the rear wall 12 of the tray intermediate its length, is a hanger support 14 having a portion 15 which extends perpendicularly to the bottom of the tray in spaced position from the back wall and

45 having a narrowed neck portion 16 bent at right angles to the portion 15 and connected to the back wall 12. Coat hangers 17 may be provided with connecting plates 18 which are slotted as at 19 for cooperation with the portion 15 of the hanger support in the manner shown in Fig. 2. The slots 19 of the hangers communicate with the edge of the plate 18 by a cross-slot which is of sufficient width to permit the hangers to be inserted over the narrowed part 16 of the hanger support. When the hangers are slid downwardly

on the narrowed part 16 of the hanger support, they are locked in place and can only be removed from the tray when they are pulled upwardly into registration with the narrowed part 16 of the hanger support.

In each of the rear corners of the tray 8 is a bracket 20 formed from a strip of metal bent to inverted U-shape, and leg 21 of the bent strip has an attaching plate 22 extending at an angle thereto and formed integral therewith. This plate is provided with apertures 23. The other leg 24 of the bracket has its lower portion bent inwardly as at 25 to provide a stop. The structure of the bracket is such that there is provided an elongated opening 26 between the bracket portions 21 and 24 which opening extends perpendicularly to the bottom of the tray when the bracket is in position. The brackets are secured to the side walls 10 and 11 of the tray by rivets or the like 27 extending through the apertures 23 of the attaching plates 22. When the brackets are installed the lower end stop 25 is spaced somewhat above the bottom of the tray and the upper end of each bracket projects above the upper edge of the rear and side walls of the tray as at 28. In order to form an end closure for the projecting portion of the bracket, tabs 29 may be bent from one of the legs of the inverted U-shaped portion as clearly shown in Figs 5 and 6.

The garment folding flap designated generally by the numeral 30 consists of a U-shaped wire frame comprising side frame parts 31 and 32 and a rear frame part 33. The front ends of the side frame parts 31 and 32 are connected to the ends of a rod 34 and the entire frame is covered with fabric or other suitable material to form a relatively strong but light-weight flap. In order to form trunnions for pivotally connecting the flap to the tray, the inner ends of the frame wires 31 and 32 are bent outwardly as at 35 (see Fig. 7) and are doubled upon extensions 36 of the wire frame part 33 which connects the side frame parts 31 and 32. Thus the trunnions, designated generally by the numeral 37, are formed as an integral part of the wire frame for the flap 30. The doubled wire parts 35 and 36 forming the trunnions may have thin metal 38 wrapped therearound, as shown in Fig. 6, to improve the appearance of the trunnions. These trunnions 37 operate within the elongated openings 26 of the brackets 20 and hingedly connect the flap 30 to the garment tray. The trunnions will rotate in the brackets to permit the flap to be swung upwardly to expose the interior of the tray and if it is desired the trunnions may be lifted to an elevated position within the extensions 28 of the brackets. When in such position, the flap may be swung rearwardly to at least a horizontal position over the back wall of the tray. When the trunnions are in an elevated position in the brackets the ends of the trunnions engage the tabs 29 to prevent transverse movement of the trunnions and flap. Such movement would be undesirable as it might cause disengagement of the trunnions from the brackets.

It is to be noted that the flap 30 is of less width than the tray to provide spaces 39 on each side of the flap whereby trousers may be folded around the edges 31 and 32 of the flap. The tabs 29 at the upper ends of the brackets, which tabs prevent transverse movement of the trunnions when the latter are in elevated position, also serve to maintain the spacing at 39 uniform.

In use of the tray, if only one garment is to be carried, only one hanger need be employed. The

coat 40 may be placed on the hanger 17 and the hanger inserted on the hanger support 14 while the flap 30 is in raised position. The free end of the coat may then be permitted to drape over the

5 front edge of the tray. Next the trousers 41 are folded around one of the side edges 31 or 32 of the flap and the flap is lowered to a position over the tray. The free ends 42 of the coat are then 10 folded over the upper surface of the flap as shown clearly in Fig. 3. Due to the elongated slots 26 in the brackets, which slots permit movement of the trunnions in a direction perpendicular to the bottom of the tray, the flap may readily 15 adapt its position to the number of garments being carried. As shown in Fig. 4, two garments 40 and 43 are supported on hangers 17 and 44 and it is apparent that in the final packing, the trunnions 37 are located in a higher position in the brackets than in Fig. 3.

20 The present invention therefore provides a very simple yet firm type of hinge connection while permitting the position of the flap to readily adapt itself to the number of garments being carried.

23 The garment folding tray when packed may be placed in the main body portion of a suitcase to be supported in an elevated position on lugs, and the cover of the suitcase is adapted to close down over the packed garment tray.

30 In the present invention wherein the flap is connected at the ends of its rear edge only to the tray, the center of the flap may be permitted to bulge or bow upwardly to allow for more bulk in the center of the tray. It is obviously very 35 desirable that the position of the tray adapt itself to the number of garments being carried within the tray because when only one suit is being carried, as shown in Fig. 3, various other articles may be packed on top of the flap 30 and 40 still be within the confines of the side walls of the tray. Thus no space is wasted.

45 Although only one form of the invention has been shown and described, it is obvious that various changes may be made without departing from the spirit of the invention and all of such changes are contemplated as may come within the scope of the claims.

What I claim is:

1. In a luggage tray having a bottom, a back, 50 and side walls, brackets mounted in the back corners of said tray and having elongated openings extending approximately perpendicularly to the tray bottom, a flap swingable over garments within the tray and having trunnions projecting 55 from its rear corners and positioned in said elongated openings of the brackets whereby said flap is pivotally connected to the tray, said trunnions being slidable in said elongated bracket openings to adapt the position of the flap to the 60 number of garments being carried in the tray, said corner brackets each having a loop portion forming a continuation of the trunnion openings projecting above the back and side walls of the tray, and tabs bent from and positioned behind 65 the projecting loop portions of the trunnion openings and engaged by the ends of the trunnions when the latter are in an elevated position for preventing transverse movement of the trunnions and flap.

70 2. In a luggage receptacle having a bottom, a back, and side walls, brackets mounted in the back corners of said receptacle, each bracket comprising a strip of metal bent to U form to provide a vertically extending elongated trunnion receiving opening having a closed upper end

which projects above the upper edge of the back wall of the receptacle, one leg of the U having an integral attaching plate projecting from an edge of said leg and projecting no higher than the upper edge of the side wall, and means extending through said plate for attaching said bracket to a wall of the receptacle.

3. In a luggage receptacle having a bottom, a back, and side walls, brackets mounted in the back corners of said receptacle, each bracket comprising a strip of metal bent to inverted U form to provide a vertically extending elongated trunnion receiving opening with the closed end of the U projecting above the upper edge of the back wall of the receptacle, one leg of the U having an integral attaching plate bent at right angles from the rear longitudinal edge of said leg, with the upper end of said plate terminating below the closed projecting end of the U and projecting no higher than the upper edge of the side wall, and the other leg of the U having its lower end bent inwardly short of the bottom of

the receptacle to form a bottom stop for the trunnion receiving opening, and means extending through said plate for attaching said bracket to the side wall of the receptacle.

5. 4. In a luggage receptacle having a bottom, a back, and side walls, brackets mounted in the back corners of said receptacle, each bracket comprising a strip of metal bent to inverted U form to provide a vertically extending elongated trunnion receiving opening with the closed end of the U projecting above the upper edge of the back wall of the receptacle, one leg of the U having an integral attaching plate bent at right angles from the rear longitudinal edge of said leg, with the upper end of said plate terminating below the closed projecting end of the U and projecting no higher than the upper edge of the side wall, and there being a tab connected to a rear edge portion of the metal strip to lie behind the upper projecting portion of the trunnion receiving opening.

WILLIAM C. CHESNUT.
